UNITED STATES PATENT OFFICE.

CHARLES H. SCARLETT, OF AUGUSTA, ILLINOIS.

HAME-TUG.

SPECIFICATION forming part of Letters Patent No. 495,617, dated April 18, 1893.

Application filed July 8, 1892. Serial No. 439,358. (No model.)

To all whom it may concern:

Be it known that I, CHARLES H. SCARLETT, a citizen of the United States, and a resident of Augusta, in the county of Hancock and State 5 of Illinois, have invented certain new and useful Improvements in Couplings for Hame-Tugs; and I do hereby declare that the following is a full, clear, and exact description of the invention, which will enable others skilled 10 in the art to which it appertains to make and use the same, reference being had to the accompanying drawings, which form a part of this specification.

My invention relates to improvements in 15 couplings or fastenings for hame tugs, the object being to provide an improved construction whereby superior results are obtained with respect to simplicity and economy, and at the same time a very efficient coupling is 20 provided which will be more durable in use and render the strain upon the draft animal less severe.

The invention consists in the novel construction and combination of parts hereinafter fully 25 described and claimed.

In the accompanying drawings: Figure 1 represents a view of a hame with my improved 30 tug coupling connected therewith. Fig. 2 is a detail sectional view of the same. Fig. 3 is a view of the tug iron. Fig. 4 is a detail view of the plate secured to the hame to which the tug iron is connected.

In the said drawings the reference numeral 1 designates the hames which may be of any 35 ordinary or usual construction. Secured to each of the hames is a metal plate 2, having bosses 3, provided with curved or hemispherical recesses. At the rear this plate is pro-

vided with a circular concave recess to receive a plate or socket 4, provided with a circular recess 5.

The numeral 6 designates a metallic bar having its front end tapered and rounded as seen at 7, and provided with a ball 8, which fits between the bosses 3, and plate 4, so that a ball and socket joint is formed. This bar is provided with loops 9, and a pin 10, to receive the hame tug 12. It is also provided with a series of holes 13, for the passage of rivets or other devices by which the tug may be fastened thereto.

From the above it will be seen, that I form a ball and socket coupling between the hame and bar 6, which will in practice be found to be very efficient, affording more comfort to the draft animal and lessening liability of chafing. It will also be more durable in use and consequently less expensive.

Having thus described my invention, what I claim is—

In a hame tug coupling, the combination with the plate adapted to be secured to a hame, provided with bosses having curved or hemispherical recesses, and having at the rear concave recesses, and the plate or socket fitting in said concave recesses and having a circular recess, of the tug iron having a curved end provided with a ball or sphere, substantially as described.

In testimony that I claim the foregoing as my own I have hereunto affixed my signature in presence of two witnesses.

CHARLES H. SCARLETT.
